COMBINATION GOLF BALL GAUGE, CLUB HEAD SCRAPER AND SPIKE TIGHTENER

Nelson L. Baldwin, 9705 Mayne St., Bellflower, Calif.,
and Oscar N. Driggs, 913 Del Mar Court, Compton,
Calif.

Filed Feb. 5, 1962, Ser. No. 68,672

Term of patent 14 years

(Cl. D52—1)

FIG. 1

FIG. 2

FIG. 3

FIG. 4

FIG. 5

FIGURE 1 is a perspective view of a combination golf ball gauge, club head scraper and spike tightener, showing our new design;

FIGURE 2 is a top plan view thereof;

FIGURE 3 is an end elevational view as viewed from the right of FIGURE 2;

FIGURE 4 is an end elevational view thereof as viewed from the left of FIGURE 2; and

FIGURE 5 is an edge elevational view as viewed from the bottom of FIGURE 2.

We claim:

The ornamental design for a combination golf ball gauge, club head scraper and spike tightener, as shown.
